UNITED STATES PATENT OFFICE.

LOREN W. RICKEY, OF SANTA CRUZ, CALIFORNIA, ASSIGNOR OF ONE-HALF TO
WILLIAM O. KERRICK, OF SANTA CRUZ, CALIFORNIA.

DRYING-FRAME SUPPORT.

Application filed October 11, 1926. Serial No. 140,937.

This invention relates particularly to a support for that type of drying frame for curtains described in my Patent No. 1,553,758, September 29, 1925.

5 It is the object of the present invention to provide a support for the drying frame that will obviate the necessity of providing an overhead suspension therefor.

It is another object to provide a structure 10 of the character indicated that is simple in form, economical in construction, and quickly and easily extended for use or collapsed when not in use.

It is also an object to provide a structure 15 of the nature indicated that will provide a firm and substantial support for the drying frame at all times.

In the drawing:

Figure 1 is a side elevation of a structure 20 embodying my invention.

Figure 2 is a front elevation of the same, part being broken away.

Figure 3 is a perspective illustration of a 25 portion of the structure showing the pivotal mounting of the frame supporting arms.

Figure 4 is a sectional view on line 4-4 of Figure 2.

Referring more particularly to the drawing, I show at 1 a heater element arranged 30 in a vertical position and provided with a vertically arranged channel iron 2 along each side edge as shown. The outer sides of these irons are provided with openings as 3 at each end as shown, and midway between 35 the ends of the channel irons 2 are formed sockets 4.

At 5 is shown a stretcher frame having a central dividing partition 6. On each side of the partition 6 is mounted a suitable curtain stretching mechanism indicated generally by the characters 7 and 7^a, the operating mechanism not being shown.

At each end of frame 5 and coinciding 45 with its longitudinal axis are pivot pins 8, and equally spaced from these pins and positioned on the four corners of the frame 5 are rollers 9. These rollers 9 are adapted to pass through the openings 3 in channel irons 2 to engage the channels therein, and the 50 pivot pins 8 are adapted to engage the sockets 4.

Pivotedly mounted on the outside of each channel 2 as at 10 is an arm 11 with its upper surface lying flush with the lower edge 55 of the adjacent socket 4, this end of the arm

preferably carrying a weighted arm 12. Upon the outer end of the arm 11 is hingedly mounted a leg 13 as at 14, this leg extending somewhat above the arm 11 and having a chain or other flexible connecting member attached thereto as shown at 15, the other end of the element 15 being attached to the upper end of the frame 1 as shown at 16.

When not in use the stretcher frame 5 lies in the plane of the channel irons 2 as shown 65 in Figure 4, this also being the position of the frame when a curtain is drying thereon. In this position both rollers 9 and pins 8 are seated in the channel 5. When it is desired to revolve the frame 5 in order that 70 the dried curtain may be removed and a wet one mounted in its place the upper end of the frame 5 is pulled outwardly thereby causing the pins 8 to roll out on the arms 11 and the bottom rollers 9 to move upwardly 75 in the channels 2. When these bottom rollers pass the sockets 4 the pins 8 move inwardly again until they engage the sockets 4 and the rollers on what is now the bottom of the frame 5 enter the openings 3 at the 80 bottom of the channels 2.

When the device is not in use the arms 11 may be swung up into a vertical position as shown in dotted lines at 17, the legs 13 folding into the position 18. The weight 12 is 85 sufficient to hold these parts in their inoperative positions.

It is to be understood, of course, that while I have herein shown and described but one specific embodiment of the invention, changes in form, construction and method of operation may be made within the scope 90 of the appended claims.

I claim:

1. A structure of the character described, comprising a supporting frame and a stretcher frame, a sliding engagement between the two frames, a supporting arm pivotally mounted on the supporting frame intermediate its ends and a support for the outer end of said arm hingedly connected thereto and extending a distance beyond the same, a flexible connection between said end of said arm and the upper portion of the supporting frame, and pivotal means carried by said stretcher frame and engaging said supporting arm.

2. A structure of the character described, comprising a supporting frame and a stretcher frame, guideways in the support-

ing frame having openings in the opposite ends thereof and rollers carried by said stretcher frame adapted to pass through said openings and engage the said guideways, pivots mounted on said stretcher frame on its longitudinal axis, collapsible supports connected to the supporting frame at a point midway between the guideway openings and means for slidably supporting said pivots **10** on the collapsible supports.

3. A structure of the character described, comprising a supporting frame and a stretcher frame, guideways mounted on the

supporting frame in opposed relation to each other and provided with openings in each end thereof and a socket midway between said openings, rollers mounted on the stretcher frame and adapted to pass through said openings and engage said guideways, pivots mounted on the longitudinal axis of said stretcher frame and adapted to engage said sockets, collapsible supports connected to the supporting frame and means for slidably supporting said pivots on the collapsible supports. **15** **20**

LOREN W. RICKEY.
